UNITED STATES PATENT OFFICE.

HENRY V. CHAMBERLAIN, OF SOMERVILLE, AND ALFRED E. TROOP, OF ROXBURY, MASSACHUSETTS, ASSIGNORS TO WILLIAM GRAY, OF AMESBURY, MASSACHUSETTS.

ILLUMINATING DEVICE.

1,000,580.

Specification of Letters Patent. Patented Aug. 15, 1911.

Application filed June 4, 1909. Serial No. 500,045.

To all whom it may concern:

Be it known that we, HENRY V. CHAMBERLAIN, a citizen of the United States, residing at Somerville, in the county of Middlesex and State of Massachusetts, and ALFRED E. TROOP, a subject of the King of Great Britain, residing at Roxbury, in the county of Suffolk and State of Massachusetts, have invented certain new and useful Improvements in Illuminating Devices, of which the following is a specification.

The object of our invention is the provision of an illuminating device which shall be adapted for use in connection with an automobile or other vehicle, or in other locations, firstly, to display a light, such as a signal light, for example a red light and thus serving as a tail light, and, secondly, to illuminate by night an object or number or a sign or a number or sign plate such as is ordinarily used upon a vehicle and bearing a license number or other designating or identifying symbol or character.

The preferred and specific embodiment of our invention consists in a double bulb incandescent lamp having two lenses, preferably of a red color, properly wired and connected with a battery, and formed with a polished sheet metal shell serving as a reflector and adapted to be secured to a vehicle body. For this latter purpose the device has a downward extension, or other vertical portion perforated for fastening screws, which may also hold the number plate detachably or permanently immediately beneath the lamp and reflector and in the field of illumination.

The vertical extension in the best form of our invention is a desirable feature which practically mounts the lamp and its reflector on the upper edge of the common metallic number plate, or provides for the insertion of such plate edgewise between depending jaws firmly secured to the reflector or lamp casing, the space between the jaws being just sufficient for the thickness of the plate, and when the screws through the jaws and plate are tightened the complete device is rigidly connected to the machine and is at once ornamental and useful.

The lamp with its reflector may have fastenings at the ends and one or more screws through its vertical portion securing the number plate in proper relative position, and removably, without disturbing the lamp.

The invention generally consists in certain novelties of construction and combinations of parts hereinafter set forth and claimed.

Figure 1 shows the illuminating device with a number plate located below the device and within the field of its illumination. Fig. 2 is a perspective view of the device. Fig. 3 is a cross section of Fig. 1 on a line adjacent to a binding post. Fig. 4 is a longitudinal sectional view of the lamp bulb holder removed from the casing.

Referring to the several figures, the numeral 1 designates the outer casing of the lamp made by fashioning a metallic sheet to a trough or concavo-convex shape so its length will be several times greater than its width; 2, the bent over edges of the metal serving to hold a glass slide in place; 3, the end pieces of the casing, one of them bent over at its edge 4 to hold one end of the glass slide in place; 5, the polished metallic reflector of substantially the same shape as the outer casing and secured within the said outer casing in any suitable way; 6, polished metallic end pieces or reflectors arranged obliquely to the longitudinal axis of the reflector 5 and secured in position by solder or otherwise; 7, holes through the walls of the casing and reflector to receive binding posts; 8, holes through the casing and reflector to allow light to pass to the lenses; 9, the lens holders secured about the holes 8 and projecting from the outer surface of the casing; 10, the lenses preferably of red colored glass set in the holders; 11, holes for screws to secure the lamp bulb holder in position within the casing; 12, a glass slide; and 13, a pivoted fastener to hold the glass slide removably in place.

To the longitudinal edge of the outer casing is secured, by solder or rivets or screws, a plate 14 having slots 15 to receive means, as straps, for detachably suspending a sign plate below the lamp and within the field or area of illumination. The plate 14 is provided with a groove 16, or a slot, formed by bending over one edge 17 of the plate and within which slot or groove is located the upper edge of a sign plate 18 having holes 19 in line with holes 20 in said plate 14, through which holes are passed screws which secure the plate 14, sign plate and lamp to an object, as the body of a vehicle.

Within the casing is a lamp bulb holder consisting of a metallic cylinder 21 having a

- binding post 22 and with internally threaded tubular sections 23 at the ends to receive the electric light bulbs 24 each threaded at the base; and a plate 25 with a turned and 5 perforated edge 26 back of which is located a metallic bar 27 with threaded holes to receive screws 28 passed through holes 11 in the casing and reflector, said plate 25 also having arms 29 bent over and soldered to the 10 tubular sections 23, as shown. The second binding post 30 is located in a hole 7 and is in contact with the plate 25. Suitable insulating material is provided between the plate 25 and the cylinder 21 and binding 15 post 22 so the circuit is complete between binding post 22, the lamp filaments, the plate 25, and binding post 30, to which binding posts conductors are attached which connect with a source of electrical energy, as a 20 battery.

Upon reference to the drawing it will be seen that the electric light bulbs are located in line with the holes through the reflector and casing and also in line with the lenses; 25 and that the polished surface of the metallic reflector will reflect the rays of light downwardly upon the sign.

From the foregoing description it becomes obvious that we have provided a device which 30 will effectively illuminate a sign or sign plate, and which also serves as a signal or tail lamp for a vehicle, and the main portions of the device may be adapted for both purposes or for either purpose.

35 One sign plate can be substituted for another however the same is connected with the plate or casing; and one bulb may be used in lieu of two, when so desired.

What we claim is:

40 1. The combination with a lamp casing having an electric lamp at the interior thereof and a glass plate closing an opening in the casing, of a number plate; and means for connecting the said casing with the number 45 plate disposed below said casing so the light from the lamp will pass through the glass plate and illuminate the number plate.

2. The combination with a lamp casing having an electric lamp at the interior thereof, of a signal lens, and a glass plate closing an opening in the casing and disposed in a plane at an angle to the plane of the lens, of a sign plate; and means for connecting the said casing with the sign plate disposed 55 below said casing so the light from the lamp will pass through the glass plate and illuminate the sign plate.

3. A combined signal and number plate 60 illuminating device for automobiles, comprising a casing having openings in angularly disposed planes, a signal lens in one of the said openings, a glass in the other opening, an electric light bulb within the interior of the casing, and means for connecting the device with a sign plate disposed 65

below the casing at such an angle thereto that the light from the lamp will be transmitted through the glass upon the face of the plate.

4. The combination with an illuminating 70 device consisting of a metallic casing of greater length than width and trough-shaped at the central portion, an electric lamp and holder at the inner surface of the casing, a lens located opposite the lamp and in line with a hole through the casing, of a sign plate having its upper edge located in line with and adjacent the casing and extending below the same, and means for detachably securing the sign plate in place, 75 said casing being provided with an opening through which light can fall upon the sign plate.

5. An illuminating device consisting of a metallic casing of greater length than width 80 and trough-shaped at its central portion, an electric lamp and holder at the inner surface of the casing, a lens located opposite the lamp and in line with a hole through the casing, a glass held in position at the edges of the casing, and means in connection with the rear surface of the casing for detachably connecting a sign plate with and below the 85 said device.

6. An illuminating device consisting of a 90 metallic casing of greater length than width and trough-shaped at the central portion, an electric lamp and holder at the inner surface of the casing, a lens located opposite the lamp and in line with a hole through the 95 casing, a glass below the lens and engaged by the edges of the casing and with the casing inclosing the lamp, and means secured to the rear surface of the casing for securing the device to a support.

7. An illuminating device consisting of a metallic concavo convex casing of greater 100 length than width and trough-shaped at its central portion, an electric lamp and holder at the inner surface of the casing, a lens located opposite the lamp and in line with a hole through the casing, a glass plate held in position by the edges of the concavo convex casing, means in connection with the casing for attaching the same to a support, 110 and also means for supporting a sign plate.

8. The combination with an illuminating device consisting of a metallic concavo convex casing of greater length than width and trough-shaped at its central portion, an electric lamp and holder at the inner surface of the casing, a glass plate held by the edges of the casing and with said casing inclosing the lamp, and a plate at the rear surface of the 120 casing, of a sign plate, and means for supporting the plate below the casing and within the area of illumination.

9. The combination with an illuminating device consisting of a metallic casing of greater length than width and trough- 130

shaped at its central portion, an electric lamp and holder at the inner surface of the casing, a glass closing the opening in the casing, and means for securing the casing 5 to a support, of a sign plate, and means for supporting the plate below and within the area of illumination.

10. An illuminating device consisting of a metallic casing of greater length than width 10 and trough-shaped at its central portion, a reflector at the inner surface of the casing, reflectors at the ends of the casing obliquely disposed to the longitudinal axis of the casing, an electric lamp and holder at the inner 15 surface of the casing, a lens located opposite the lamp and in line with the holes through the casing and reflector, and a plate secured to the rear surface of the casing back of the electric lamp.

20. 11. An illuminating device consisting of a metallic casing of greater length than width and trough-shaped at its central portion, a holder secured within and to the casing midway of its ends, two electric lamps with 25 their bases secured to opposite ends of said holder, two lenses, one located opposite each lamp and in line with a hole through the casing, a glass plate closing the opening in the casing, and means in connection with the 30 casing for securing the device to a support.

12. The combination with an illuminating device consisting of a metallic casing of greater length than width and trough-shaped at its central portion, two electric 35 lamps and a holder at the inner surface of the casing, two lenses, one located opposite each lamp and in line with a hole through the casing, a reflector at the inner surface of the casing, a glass plate which with the casing 40 entirely incloses the lamps, and means in connection with the casing for securing the device to a support, of a sign plate disposed below and at an angle to the glass plate in the casing.

45. 13. An illuminating device consisting of a metallic casing of greater length than width and trough-shaped at its central portion, two electric lamps and a holder at the inner surface of the casing, two lenses, one located 50 opposite each lamp and in line with a hole through the casing, a reflector at the inner surface of the casing, a sliding glass plate closing the opening in the casing, and means located at the rear surface of the casing opposite the lenses for securing the device to a 55 support.

14. An illuminating device consisting of a metallic casing of greater length than width and trough-shaped at its central portion, 60 two electric lamps and a holder at the inner surface of the casing, two lenses, one located opposite each lamp and in line with a hole

through the casing, a glass plate disposed at an angle to the plane of the lenses and with the casing entirely inclosing the lamps, a 65 plate secured to the casing, and means in connection with said plate for supporting a sign plate.

15. An illuminating device consisting of a metallic casing of greater length than width 70 and trough-shaped at its central portion, two electric lamps and a holder at the inner surface of the casing, two lenses, one located opposite each lamp and in line with a hole through the casing, a glass plate located in 75 a plane at an angle to the plane of the lenses, and a bracket at the rear surface for the connection of the device with a sign plate.

16. An illuminating device consisting of a casing, an electric lamp and holder at the 80 inner surface of the casing, a lens in the casing in front of the lamp, a glass plate disposed at an angle to the plane of the lens and with the casing entirely inclosing the lamp, a plate at the rear surface of the casing, a sign plate, and means for supporting the sign plate below the casing and within 85 the area of illumination.

17. An illuminating device consisting of a casing, an electric lamp and holder at the 90 inner surface of the casing, a lens located in front of the lamp, a plate at the rear surface of the casing, and a sign plate; said sign plate being supported by the plate at the rear of the casing and within the area of 95 illumination.

18. An illuminating device consisting of a casing, an electric lamp and holder at the inner surface of the casing, a lens located in front of the lamp, a plate at the rear surface 100 of the casing, a sign plate supported by the said plate within the area of illumination, and a glass below the lamp and above the sign plate.

19. The combination in an illuminating 105 device for automobile number plates, of a casing having a light producing means at the interior thereof, a signal lens set in the front of the casing, a glass plate set in the casing at its lower edge and below the light producing means, which latter is inclosed by the casing, lens, and glass, a number plate disposed below the said glass plate so said number plate will be illuminated by the light, and means for detachably securing the 110 115 said casing and number plate to a vehicle.

In testimony whereof, we affix our signatures in the presence of two witnesses.

HENRY V. CHAMBERLAIN.
ALFRED E. TROOP.
